UNITED STATES PATENT OFFICE.

GEORGE GEGENHEIMER, OF BALDWIN, LONG ISLAND, NEW YORK, ASSIGNOR TO
GOLDING BROS. COMPANY, OF NEW YORK, N. Y., A CORPORATION OF NEW YORK.

DESIGN FOR A FABRIC.

59,834.

Specification for Design.

Patented Nov. 29, 1921.

Application filed July 16, 1921. Serial No. 485,296. Term of patent 7 years.

To all whom it may concern:

Be it known that I, GEORGE GEGENHEIMER, a citizen of the United States, residing at Baldwin, Long Island, in the county of Nassau and the State of New York, have invented a new, original, and ornamental Design for a Fabric, of which the following is a specification, reference being had to the accompanying drawing, forming a part thereof.

The figure is a plan view of a section of the textile fabric, embodying the design.

I claim:

The ornamental design for a fabric, as shown.

GEORGE GEGENHEIMER.

Witness:

C. H. LUERSSEN.
